SPINNING MACHINE WHIRL

Thomas A. Darr, Cumberland, Md.

Application April 23, 1934, Serial No. 722,023
Renewed March 7, 1935

3 Claims. (Cl. 118—66)

The invention relates to a spinning machine whirl and more especially to a ball bearing mount for a spinning machine whirl.

The primary object of the invention is the provision of a whirl of this character, wherein a ball bearing mount therefor is had at the location of the traverse, so that free movement is assured to the whirl and lubricant will be prevented from being thrown out of the bearing when the whirl is rotated at high speed, and increased life is assured.

Another object of the invention is the provision of a whirl of this character, wherein a bushing is carried by the spindle of the spinning machine, the bushing being supported about a sleeve or tube which fits the said spindle and this bushing couples the traverse with the whirl, and in the assembly of the bushing, bearing balls are fitted therewith for easy travel of the whirl.

A further object of the invention is the provision of a whirl of this character which is simple in construction, thoroughly reliable and efficient in its purpose, affording increased wearing quality, novel in assembly and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:
Figure 1 is a fragmentary top plan view showing the assembly in accordance with the invention.

Figure 2 is an elevation partly in vertical section.

Figure 3 is a fragmentary vertical transverse sectional view.

Similar reference characters indicate corresponding parts throughout the several views in the drawing.

Referring to the drawing in detail, A designates generally a portion of the spindle rail of a spinning machine and B a portion of the traverse of said machine, respectively, the said traverse being also known as a lifting rail and being arranged above the spindle rail A. Removably fitted in the spindle rail A is the vertical spindle 10, and the traverse or lifting rail, in its arrangement above the spindle rail, loosely receives therethrough the spindle 10.

Upon the spindle 10 is fitted the sleeve or tube 11 which, near the lower end portion thereof, has

formed therewith an external annular shoulder 12 against which rests upper and lower inside and outside ball cones 13 and 14, respectively, these being held within a cup-shaped bushing 15 and having arranged therewith bearing balls 16. The bushing is formed with an external key 17 received in a keyway 18 in the traverse or lifter rail B, so that the said bushing will be held against turning movement when fitted within the opening or clearance therefor in the traverse or lifting rail. 10 Threaded internally of the bushing is its cap 18, this fitting the upper end of said bushing, while at the lower end of the bushing is a packing gland 19. The bushing exteriorly thereof is formed with the annular rest flange 20 which is 15 at one side of the traverse or lifting rail, while externally threaded upon the bushing at the other side of said traverse or rail is the lock nut 21, so that in this manner the bushing is made fast to the traverse or lifting rail. Upon the sleeve or tube 11 is mounted the whirl or pulley 22 and the same rests upon a shoulder 23 formed on the tube or sleeve 11 which is above an outside cover 24 for the upper end of the bushing.

The tube or sleeve 11 has fitted therewith, as 25 usual, the bobbin 25 and overhanging this bobbin is the cap 26, the latter being carried by the spindle at its upper end. Formed in the bushing 15 is an oil duct 27 leading to the bearing balls and cones therein, the outer end of the duct being 30 closed by a removable plug 28.

The spindle rail has formed therewith a guide 29 through which works the lift rod 30 for the traverse or lifting rail B, the rod 30 being engaged with a slide or jib 31 working upon or traveling on a guide 32 which functions to prevent the twisting or turning of the lifting rail or traverse, the whirl or pulley 22 being driven by a belt (not shown) and high speed of such whirl tends to twist or turn the traverse or lifting rail. 40

What is claimed is:

1. The combination with a spinning machine spindle and a lifting rail, of a tube loosely fitted upon said spindle, outside and inside cones arranged about the tube, bearing balls interposed between the outside and inside cones, a bushing keyed in the lifting rail and enclosing said cones and bearing balls, a cap fitting the top of the bushing, a packing gland at the lower end of the bushing and about said tube, a whirl fixed to the tube above the bushing, a cover for the upper end of said bushing, the said bushing having a lubricant duct leading to the interior thereof, and a removable plug closing the outer end of the duct. 45
2. The combination with a spinning machine 50

- spindle and a lifting rail, of a tube loosely fitted upon said spindle, outside and inside cones arranged about the tube, bearing balls interposed between the outside and inside cones, a bushing 5 keyed in the lifting rail and enclosing said cones and bearing balls, a cap fitting the top of the bushing, a packing gland at the lower end of the bushing and about said tube, a whirl fixed to the tube above the bushing, a cover for the upper end 10 of said bushing, the said bushing having a lubricant duct leading to the interior thereof, a removable plug closing the outer end of the duct, and means cooperating with the lifting rail to prevent tilting or turning thereof.
- 15 3. The combination with a spinning machine spindle and a lifting rail, of a tube loosely fitted

upon said spindle, outside and inside cones arranged about the tube, bearing balls interposed between the outside and inside cones, a bushing keyed in the lifting rail and enclosing said cones and bearing balls, a cap fitting the top of the bushing, a packing gland at the lower end of the bushing and about said tube, a whirl fixed to the tube above the bushing, a cover for the upper end of said bushing, the said bushing having a lubricant duct leading to the interior thereof, a removable plug closing the outer end of the duct, 5 means cooperating with the lifting rail to prevent tilting or turning thereof, and means exteriorly engaged on the bushing for securing it in the lifting rail. 10
